OR D 14,565

No. 14,565

JAN 29, 1884

UNITED STATES PATENT OFFICE.

LOUIS CASPER, OF MERIDEN, CONNECTICUT.

DESIGN FOR A SALT AND PEPPER BOX.

SPECIFICATION forming part of Design No. 14,565, dated January 29, 1864.

Application filed October 23, 1863. Term of patent 3½ years.

To all whom it may concern:

Be it known that I, LOUIS CASPER, a citizen of the United States, residing at Meriden, in the county of New Haven and State of Connecticut, have invented certain new and useful Improvements in Designs for Salt and Pepper Boxes or Receptacles, of which the following is a specification, reference being had therein to the accompanying drawing, in which I have represented my design in side view.

The object of my design is the ornamentation of salt and pepper boxes and similar articles; and it consists in giving such articles the form or shape of a squirrel or like animal in an upright position; also, in the frosting or similar treatment of the exterior surface to represent the fur of the animal.

A indicates the box, made in the form of the body of the animal, and B the cap, made in the form of the animal's head, and screw-threaded into the body, as indicated. The

animal is placed in an upright position on its haunches, with a nut or other article of food between its forepaws. In the top or crown of the animal's head I form holes b. The body and head represent the fur of the animal.

The design is ornamented by one or more circumferential lines, a, formed on the neck portion of the squirrel, as clearly shown.

Having described my design, what I claim, and desire to secure by Letters Patent, is—

The design for salt and pepper receptacles, consisting in the representation of a squirrel having its neck portion ornamented by one or more circumferential lines, substantially as shown and described.

In testimony whereof I affix my signature in presence of two witnesses,

LOUIS CASPER.

Witnesses:

ROBERT H. CURTIS,
CHARLES CASPER.
